UNITED STATES PATENT OFFICE.

HARRY L. OWEN, OF YORK, PENNSYLVANIA, ASSIGNOR TO GENERAL ELECTRIC COMPANY, A CORPORATION OF NEW YORK.

ROTARY ASBESTOS-APPLIER FOR WIRE-COVERING MACHINES.

1,098,050.

Specification of Letters Patent.

Patented May 26, 1914.

Application filed January 20, 1909. Serial No. 473,243.

To all whom it may concern:

Be it known that I, HARRY L. OWEN, a citizen of the United States, residing at York, in the county of York and State of Pennsylvania, have invented certain new and useful Improvements in Rotary Asbestos-Appliers for Wire-Covering Machines, of which the following is a specification, reference being had therein to the accompanying drawing.

My invention relates to machines for and the process of covering wire with insulating material, such as asbestos fiber or other suitable material, and more particularly to the actual application of the fiber to the wire.

Most of the machines now employed for this purpose are unsatisfactory owing to the fact that the wire is conveyed from the stock reel around numerous corners which tend to bend and harden the wire (which has been found very detrimental to the uses for which the wire is intended). Furthermore, the asbestos fiber cannot be applied in its proper and best condition, that is, in the state in which it is received from the doffer rolls of the carding machine, nor can it be evenly applied to the wire by any of the machines heretofore employed. In many of the machines for this purpose now in use the wire as it progresses or is drawn through the machine is constantly revolved and passes through dies and straightening devices which are detrimental and to a certain extent destroy the qualities of the wire.

By my invention the wire is drawn and progresses through the covering machine in a straight line from the stock reel without being axially revolved and by my novel means of applying the insulation the asbestos fiber is applied in an overlapping spiral about the wire in a perfectly even state. Moreover, by my method of handling the material the asbestos retains all of the flocculent qualities which it has when it comes from the doffer rolls of the carding machine.

The method of preparing the asbestos fiber referred to herein is fully described in my Patent No. 1,053,108.

In carrying out my present invention I take the asbestos from the doffer rolls of the carding machine in the form of a continuous web, which web is rolled upon itself, preferably with paper between the turns as described in the patent above re-

ferred to. This asbestos is then applied to the wire in a spiral so that the turns overlap, the wire having been first coated with adhesive material. The wire does not rotate while traveling through the machine but the rolls of asbestos are caused to rotate around the wire so as to spirally wrap the same. After the wire has received this spiral wrapping it passes through devices which thoroughly compress the fibers and smooth down the overlapping joints.

In the accompanying drawing I have illustrated one form of machine, which is capable of carrying out the various steps embodying my invention.

Referring to the accompanying drawings forming a part of this application, Figure 1 is a side elevation of a wire covering machine embodying the present invention; Fig. 2 is a partial end view of the same showing the mechanism for operating the wire winding reel; Fig. 3 is an elevation of one face of the covering portion of the machine; Fig. 4 is a partial sectional view of the same; Fig. 5 is a sectional view taken on the line $\alpha-\alpha$ of Fig. 3; Fig. 6 is a detail of the sliding reel; Fig. 7 is a detail view of the reel spindle and hub; Fig. 8 is a plan view of the rear end of the machine; and Fig. 9 is a detail of the sliding nut.

Referring to the drawings, 1 indicates a suitable supporting frame upon which is mounted the stock reel 2 from which the bare wire or conductor 3 is drawn by having been given one complete wrap around the peripheral groove in the sheave 4 which is operated by a wormwheel 5 meshing with the worm 6 mounted upon the driving shaft 7. The wire 3 after leaving the reel 2 is drawn through the guide 8 and the straightening die 9 of any suitable design and thence above and in contact with the revolving applying wheel 10 which is revolved within the composition pot 11 by the link belt 12 driven from the main driving shaft. The wire having been coated with adhesive composition is drawn through the center of the asbestos applier 14. This applier forms an important part of the applicant's invention and will be hereinafter fully described in detail. After leaving the applier the wire passes under the drip pot 13 which applies an outer coating of waterproofing material but this may be dispensed with if desired, as by my method it may not in all cases be

105
110

found necessary. The wire is now conveyed through the compressor 14', which forms the subject matter of a separate application and need not be specifically described herein. Directly in the rear of said compressor is situated a heater or cooler, as the case may be, shown here as a cooler 15 for cooling the coating composition applied by the drip pot 13. If a heater is employed the material will be baked upon the wire. The wire is now led around the sheave or drawing wheel 4 above referred to which draws the wire through the machine and thence between the guide rolls 16 to the winding reel 17 upon which the wire is wound as the reel is rotated by the action of the belt 18 which runs over the pulley 19. The object of employing a pulley is that it will slip to compensate for the variation of speed attained by the reel 17 due to the positive delivery of the wire from the wheel 4 and the increase in diameter of the wire upon the reel 17.

The traverse mechanism for the wire winding reel 17 consists of a shaft 20 provided with right and left handed screw threads and journaled in the bearings 21 situated on the supporting frame 1. One end of the shaft 20 is provided with a spline 22 to allow the driving pulley 23 to slide longitudinally thereon and at the same time to rotate said shaft by the engaging feeder or key. Upon the end of the frame 1 is pivoted the balance arm 24 which has attached thereto the shifting lever 25 having its ends pivoted to the outer end of levers 26 mounted upon extensions 27 of the bearing brackets 21. Attached to the inner end of the levers 26 are the screw threaded boxes 28 which are thrown into and out of engagement with the threaded shaft 20 by means of the inclined surfaces 28'. The balance arm 24 has a pin and slot connection with the lever 25 so that when the balance arm is moved past its vertical position it will drop over in the direction in which it is being moved. When the pin reaches the end of the slot the momentum of the arm 24 shifts the lever 25 longitudinally and thereby turns the levers 26 on their pivots so as to shift one box into engagement with the screw threaded shaft 20 and shift the other box out of engagement therewith to reverse the direction of movement of the reel. In order to move the balance arm 24 I provide a rod or roller 29' which projects into engagement with the inside edge of the flanges of reel 17. By this arrangement when the reel 17 travels far enough so that the wire has reached the end of its travel in one direction the balance arm 24 will be in the vertical position so that a very slight further movement throws the lever 24 over center and shifts the lever 25 which reverses the direction of motion 65 of the reel as above described. This revers-

ing arrangement forms no part of my invention since devices of this general character are in common use.

The asbestos coverer or applier 14 is constructed as follows: It comprises a housing or case 29 which is divided horizontally into two parts or members, the lower part or member being secured upon the supporting frame 1. Bearing brackets 30 are provided upon the lower member of the housing in which are rotatably mounted the shafts 31 carrying the V-shaped friction wheels 32 and the sprocket wheels 33 which are connected together by the sprocket chain 34. One of the shafts 31 is provided with the sprocket wheel 50 (Fig. 1) which is driven by a chain 35 from the main shaft. The upper member of the housing 29 is provided with a bearing bracket 36 in which is mounted the V-shaped idle or retaining friction wheel 37. Rotatably and frictionally mounted upon said friction wheels 32 and 37 is a circular plate 38 provided with a V-shaped groove in its periphery for receiving the friction wheels 32 designed to drive and propel the plate and also to receive the retaining wheel 37. The center of the circular plate 38 is formed with an orifice 39 which allows the wire to pass therethrough. Parallel and adjacent to the rear surface of said plate 38 and integral with the lower member of the housing 29 is a horizontal brace 40 having an orifice 39'. Secured to this brace is an internal gear 41 in axial relation to the plate 38. Journaled in the plate 38 adjacent to the orifice 39' is a shaft 42 upon which is rigidly secured the pinion 60 meshing with the internal gear 41. On the other end of the shaft 42 and upon the opposite side of the plate 38 is secured the driving pulley 43. Upon the same face of the plate 38 and between the pulley 43 and the orifice 39' are mounted the small rollers 44 and 45. These rollers are mounted upon studs 46 and 47 which are screw threaded into the plate 38. It may here be stated that the diameter of the roller 44 and the ratio of the gearing for driving the same may be varied as required by the different sizes of the wire to be treated.

Rotatably mounted in the plate 38 with its end projecting therefrom is the shaft 48 having a pulley 49 which is driven by the belt 50' from the periphery of the internal gear 41. Upon the forward end of the shaft 48 is detachably secured a tape reel which is preferably of my novel construction shown in Fig. 7. This reel will be seen to consist of a hub 51 formed with shoulders 52 and screw threaded ends 52'. Detachably secured upon the ends of the hub 51 and retained in contact with the shoulders 52 by the nuts 54 are the circular flanges or sides 56. Diametrically opposite from the shaft 48 the plate 38 is provided with a rec-

tangular slot or orifice 55 within which is slidably mounted a box 57 carrying a stud 58 upon which is detachably secured one of the above referred to tape reels 58'.

5 The operation of the device as a whole is as follows: The tape reel having wound thereon a supply of tape with the asbestos fiber deposited thereon as received from the carding machine is secured upon the stud 58 with the flange 56 removed therefrom. The end of the tape is brought up and over the roller 44 where it will be in contact with the wire or conductor 3 as the latter progresses through the orifice 39 as previously described. The tape is now carried around the driving pulley 43 which drives said tape by frictional contact, and thence over the roller 45. The tape then passes to an empty tape reel mounted upon the shaft 48 rotated by the belt 50'. It will be seen that as the tape is unwound from the reel it is always drawn toward the roller 44, the reel of tape always keeping close to the roller 44 by reason of the movement of the box 57 in the radial slot 55. Only a small portion of the coated surface of the tape is therefore exposed to the wire, thus preventing the asbestos fibers from being prematurely removed therefrom. As the plate 38 is revolved about the traveling wire 3, the tape is simultaneously wound from one reel to the other with its surface which carries the deposited asbestos in contact with the wire 3. This wire 3 having previously been coated with adhesive composition, the asbestos fiber will be deposited thereon in the form of an overlapping spiral which may be regulated as to the number of wraps per inch and the amount of fiber deposited by the speed at which the wire 3 is made to progress through the device. As the tape leaves the wire 3 after having the asbestos fiber removed therefrom it is wound upon the empty reel on the shaft 48 which is revolved by the belt 50' in such a manner that the slippage of the belt will compensate for the increasing diameter of the tape upon said reel due to the more positive feed of the driving pulley 23. When the tape is exhausted the empty reel 28 is transferred to the shaft 48. A full reel is then placed upon the stud 58 and the operation repeated.

Having thus described my invention what I claim as new and desire to secure by Letters Patent is:—

1. A device for applying asbestos fiber to conductors, comprising a housing mounted in axial relation to and surrounding said conductor, a circular carrier surrounding said conductor and rotatably mounted within said housing, an internal gear secured to said housing in axial relation thereto, a shaft mounted in the body of said carrier with its ends extending therefrom, a pulley secured upon one end of said shaft and a

belt connecting said pulley with the periphery of said internal gear, a stud formed with a box slidably mounted in said carrier and capable of a free radial motion therein, a discharging tape reel adapted to carry asbestos covered tape detachably mounted upon said stud, a receiving tape reel detachably secured upon the shaft and adapted to receive the tape from the discharging tape reel, rollers mounted upon said carrier and adapted to guide the tape into contact with the surface of the conductor during its passage from the discharging reel to the receiving reel, a driving shaft mounted in said carrier, a friction driving pulley secured upon one end of said shaft in driving contact with said tape, a spur gear secured upon the other end of said shaft in mesh with said internal gear, and rollers mounted within said housing for the purpose of retaining and rotating said carrier within said housing and about said conductor.

2. In a machine of the class described, in combination with means for feeding the wire, means for delivering the flocculent insulating material to the wire, comprising a housing mounted upon said machine in axial relation to said wire, a circular carrier rotatably mounted within said housing, tape reels detachably mounted upon said carrier, and adapted to hold the insulating material, means for automatically transferring the tape from one reel to the other reel actuated by the revolution of said carrier, and means for bringing the surface of said tape into contact with the surface of said wire during its passage from one reel to the other.

3. In a machine of the class described, in combination with means for feeding a wire, a pair of reels mounted for rotation around said wire, a tape having asbestos fiber thereon extending between said reels and in contact with the wire, and means for causing said reels to rotate on their own axes so that the tape will be wound upon one reel and simultaneously unwound from the other.

4. In a machine for applying flocculent asbestos fiber upon the surface of electric conductors, in combination with means for feeding the conductor through the machine and means for coating the surface thereof with an adhesive composition, of a housing mounted upon said machine in axial relation to and surrounding said conductor, a ring mounted within said housing and adapted to be rotated about said conductor as its center, tape reels rotatably mounted upon said ring and adapted to be revolved about said conductor, and means for carrying said tape from one reel to the other in contact with the coated surface of said conductor.

5. A machine for applying an asbestos covering to wire comprising a support,

means for rotating it, a reel on said support for carrying a ball of asbestos carrying tape, a second reel on said support for receiving the tape, and means for operating the reels.

6. In a machine of the class described, in combination with means for feeding the wire and means for applying adhesive coating thereto, a carrier rotatably mounted in axial relation to said conductor, a pair of reels mounted thereon, a tape having asbestos fiber upon its surface extending between said reels and in contact with the wire,

means for causing said reels to rotate on their own axes so that the tape will be wound upon one reel and simultaneously 15 unwound from the other, and means for rotating said carrier.

In testimony whereof I affix my signature in presence of two witnesses:
